UNITED STATES PATENT OFFICE.

WILLIAM W. LASKER, OF BROOKLYN, NEW YORK, ASSIGNOR, BY MESNE ASSIGNMENTS,
TO POWERS ACCOUNTING MACHINE CORPORATION, OF NEW YORK, N. Y., A COR-
PORATION OF DELAWARE.

NONPRINT MECHANISM OF PRINTING TABULATORS

Original application filed March 28, 1917, Serial No. 158,142. Divided and this application filed April 3, 1918. Serial No. 226,500.

To all whom it may concern:

Be it known that I, WILLIAM W. LASKER, a citizen of the United States, residing in Brooklyn, in the county of Kings and State of New York, have invented certain new and useful Improvements in Nonprint Mechanism of Printing Tabulators, of which the following is a specification.

This invention relates to a printing tabulator of the kind adapted to be controlled by perforated cards, and relates more particularly to matter divided from my co-pending application Serial No. 158,142 filed March 28, 1917, for printing tabulators.

The invention herein described relates particularly to the mechanism of said printer tabulator for at will rendering the printing mechanism thereof inoperative for printing items, and for automatically rendering it operative when a total is taken and, therefore, only as much of the printing tabulator is described herein as is necessary to show the connection between the matter of the original application and the matter claimed herein.

While herein and in said application minute details of one of many possible embodiments of the invention are described, the invention is not limited to these since various changes may be made in the details of construction and combination without departing from the spirit and scope of the invention as claimed.

One object of the invention is to improve generally apparatus of this kind.

Another object of the invention is to provide an economical and efficient means for effecting the printing by the reciprocation of the paper carriage when the printing type have been set.

Another object is to provide convenient means for rendering the carriage reciprocating mechanism inoperative at will and for automatically rendering the reciprocating mechanism operative when totals are printed.

Another object is to provide an efficient and convenient total signal means for indicating the fact that a figure is a total, this

means operating by shifting the carriage to

one side as the total is being printed, whereby the total is offset from the listed column. Still further objects and advantages of the present improvement will be set forth in the following description and drawings in which

Fig. 1, is a side elevation of the printing and calculating machine constituting a part of the printing tabulator.

Fig. 2 is an interior side elevation partly in section of the type setting and calculating elements.

Fig. 3 is an enlarged perspective view of the total taking shaft and the actuating arms for the accumulating mechanism.

Fig. 4 is a fragmental vertical sectional view taken on a vertical plane passing through the total taking shaft.

Fig. 5 is a vertical sectional view showing the total taking shaft shifted into position to take a total. 70

Fig. 6 is a detail plan view of the various operating cams.

Fig. 7 is an end elevation of the printing carriage. Fig. 8 is a front elevation of the carriage.

Fig. 8 is a front elevation of the carriage. Fig. 9 is a sectional view of a detail taken on the lines 7—7 of Fig. 8. Fig. 10 is a front elevation of the carriage.

Fig. 10 is a face view of the print and non-print locking plate. 80
The invention herein relates to a printing tabulator which is adapted to be actuated by perforated cards, which in their passage through the machine operate elements for setting up type commensurate with the designations on the card and actuate an accumulating mechanism for accumulating therein the data recorded on the card perforations whereby the total accumulated data may be computed and then printed by the printing elements of the machine. 85 90

The embodiment illustrated in said co-pending application comprises a main frame, the card feeding mechanism, the card analyzing mechanism, and an upper base 10 (Fig. 1) on which the accumulating and printing mechanism 12 hereinafter to be described and the paper carriage 13 are mounted.

The cards to be analyzed are disposed in a 100

receptacle and are fed to the analyzing mechanism in which, as shown in said co-pending application, analyzing pins, which find perforations in the cards being analyzed, pass upwardly therethrough and engage extension pins, which in turn actuate registering stops 14. After the cards have been analyzed they are discharged into a suitable receptacle.

10 The first step in the operation of the typesetting and tabulating mechanism, consists in the pushing up of the various stop pins 14 (Fig. 2) by means of the extension pins, which are actuated by the various perforations in the cards as they pass through the machine. A specific description of the stop pins, their supporting means, and the means for returning them to normal position after they have set in motion various other parts 20 of the typesetting and tabulating mechanism is given in said co-pending application.

25 The registering stops 14 correspond in number to the extension pins except that there are no extension pins or registering stops 14 to correspond with the analyzing pins that analyze the zero perforations in the cards. Each row of registering stops 14 has a zero stop 16 associated therewith, which is normally in zero stopping position 30 and will remain so unless one of the registering stops 1 to 9 inclusive associated therewith is actuated and therefore it is unnecessary for a zero analyzing pin to actuate or cooperate with a zero stop 16.

35 Herein the part of the accounting machine to the left in Fig. 2 will be considered the forward part of the machine while that to the right in Fig. 2 will be considered the rear of the accounting machine.

40 The registering stops 14 in the present instance are arranged in a suitable number of rows having ten stops in each row, the stops of each row corresponding to the integers 9 to 1 inclusive and zero, the stop 9 being at the forward end of the machine and the zero stop at the rear end thereof. The stops 14 corresponding to the integers 1 to 9 inclusive are each composed of a flat body portion comprising a head having forwardly 45 projecting portion 17, a cam face 18, a small rectangular shaped abutment 19 made on one side of the pin and adjacent to its upper end, an elongated body portion 20, and a lower restoring notch 21 on the rear edge thereof.

50 The stops 14 have their projections 17 normally resting on an upper stop plate 22 and extend down through a lower stop plate 23. The stop plates 22 and 23 have openings therein corresponding in number to the stops 14 and zero stop 16 in registry with each other whereby the pins may reciprocate through them.

The stop plates 22 and 23 are indirectly supported on the cheek plates 34.

55 The zero stops 16 are formed somewhat

similar to the stops 14 and have a forward projection 36 at their upper end and a cam face 37 on the forward edge extending upward from the extension 36 and a recess 38 in its rear edge.

70 Means is provided for anchoring the various registering stops 14 that are actuated by the extension pins and also holding the zero stops 16 in position for causing an actuation of the corresponding typesetting 75 and tabulating elements. This anchoring means is fully shown and described in said co-pending application and is not claimed herein.

78 The zero stops 16 are normally disposed in raised position and whenever a stop 14 is actuated to the raised position by means of the plungers 12, simultaneously therewith the zero stop 16 in that row will be lowered.

80 In order to accomplish this result an elongated lever 62 (Fig. 2) is provided for each row of stops 14, which lever is provided with a plurality of lugs 63 arranged in a straight line and all extending in the same direction, each lug 63 also extending into one 85 of the recesses 21 of the stop pins 14. The front ends of the levers 62 are pivoted on a suitable shaft which is supported within the cheek plates 34 of the machine. The rear ends of the lever 62 are provided with lugs 90 66 which are slidably and pivotally mounted in slots 67 at the rear ends of the links 68, which links are pivoted on a shaft 69 supported by the cheek plates 34. The front 95 end of the links 68 are provided with lugs 70 100 which are arranged to slide within a recess 38 formed in the rear edge of the naught stops 16.

105 Supported by the cheek plates 34, is a comb plate 71 the upper end of which is slotted to permit the lever 62 to extend therethrough and be guided thereby. A coil spring 71' is strained between the lever 62, and the lower edge of the said plate 71 for the purpose of normally raising the 110 naught stops 16 into the position shown in Fig. 2. When one of the stops 14 is raised, the actuation of the lever 62 by means of the cooperation of the slot 21, carried by the stop, with the plug 63, carried by the 115 lever, will cause the links 68 to be actuated which will in turn lower the stop 16 of the row in which the stop pin 14 has been raised.

120 As has been heretofore described the first action that takes place when the machine is started, is the raising of the various stop pins 14 by the actuation of the extension pins which are in turn controlled by the perforations in the cards passed through the 125 machine. After a card has transferred its data to the pins 14 by raising them, and has passed from the machine, means is provided for returning the pins 14 to their normal lower position for actuation by the next in- 130

coming card. This means for returning the stop pins to their normal position is described in detail in said co-pending application.

5 A lever 72 is provided having a bifurcated lower end 73 which straddles the main drive shaft 74 which provides the driving means, for the entire typesetting and calculating mechanism. This lever 72 is provided with 10 a pin 72' upon which is rotatably mounted a roller 75 which is arranged to roll within a cam slot 76 in a suitable cam on the shaft 74.

There is provided and described in said 15 co-pending application, though not shown or claimed herein, a means operatively connected with said lever 72 whereby the stops 14 which have been set by the perforated cards, are released by the aforementioned 20 anchoring means after they have performed their functions. As soon as the pins 14 are freed, the lever 62 will be pulled down by means of the coil spring 71', and in its downward movement the lugs 63 carried thereby 25 will engage the slots 21 of the stop pins 14 and pull them downward to their normal lowered position.

The naught stop pins 16 are arranged to 30 normally retain or hold back reciprocating rack bars 82, which during their reciprocation actuate typesetting elements. As heretofore described, the raising of a stop pin will lower the naught stop so that upon the 35 actuation of a stop pin, the reciprocating rack bar associated therewith will be released and be permitted to run forward until it engages a raised stop pin 14. During 40 their reciprocation the reciprocating members have actuated the type setting elements and upon being stopped by the raised stop pins will hold the typesetting elements in a 45 position to set type corresponding with the number of the raised stop pins. A detailed description of the reciprocating rack bars and their connection and cooperation with the naught stops, stop pins and typesetting elements will now be described.

The reciprocating rack bars each comprise a relatively thin bar shaped body portion 82 which is provided with a longitudinal slot 83 that is adapted to slide along a transverse bar 84, secured to the cheek plates 34. A transverse bar 85 is also provided which serves a support for the forward end 50 of the bar 82. The bar 85 is rigidly fastened to the cheek plates 34. A second relatively thin bar shaped member 86 is pivoted at its front end to a pivot 87 carried by the front end of the bar 82. The upper edge of the 55 bar 86 is provided with a recess 88 to receive a bar 89 which is reciprocated by means hereinafter to be described, and during its reciprocation will move both the bar 82 and the bar 86 connected thereto. The 60 bar 86 is provided with a cut away portion 65

90 so as to lessen the depth of the said bar to enable it to slide above the shaft 84 and at the same time permit the outer ends of the bars 82 and 86 to remain parallel with each other. A spring 91 is strained between 70 the free end of the bar 82 and a vertically extending arm 92 which is made integral with the inner end of the bar 82.

A horizontally extending pin 96 is carried by one side face of the bar 82 which is 75 adjacent to the bar 86 and pivotally mounted upon which is a bell crank lever 97, the outer end of which is provided with a horizontally extending pin 98 which is reciprocatively movable in a slot 99 made in the 80 bar 86. The other end of the lever 97 is provided with a lug having a cam front face 101 and a right angular notch forming a rest 103 (Fig. 2). The upper edge of the bar 82 is provided with an upstanding abutment 104 having a vertical front wall 105 and an inclined or cam rear wall 106. The bottom edge of the bar 82 is provided with an abutment 104' provided with a vertical front wall 105' and a cam rear wall 106' 85 the purpose of which will be hereinafter set forth.

The bar 89 which as heretofore described, is for the purpose of reciprocating the bars 82 and 86 is itself reciprocated in 90 the following manner, reference especially being made to Fig. 1.

The bar 89 which is rectangular in cross section is rigidly connected at each end to a slide 107, which is reciprocatable between 100 rollers 108 forming guideways therefor. A slot 109 is made in each cheek plate 34, which receive a roller 110 revolvably mounted on the shaft 111 secured to the rear end of the said slides 107. The front end of the 105 slides 107 are provided with horizontally extending pins 112, which are reciprocatably mounted in slots 113 formed in the upper ends of levers 114, the lower portion of which are triangularly shaped, one corner 110 being pivoted to stud shafts 115 carried by each cheek plate 34. The other corner of the triangular shaped levers 114 carries a roller which arranged to roll within a suitable cam groove in a cam carried on the 115 shaft 74.

Returning now to the rack bars 82, the top edge of the forward portion of the said bars 82 are provided with gear teeth 119 which are in mesh with a gear 120 (Fig. 2) 120 secured to type segments 121, which have bearing on a transverse shaft 122 carried between the cheek plates 34 which segments have an arc shaped rear edge provided with gear teeth 123 which will hereafter be described. The front edge of the segments 121 are also made arc shaped and are provided with rectangular notches to receive the upturned ends of type 126. The rear 125 ends of the type are also provided with a 130

laterally turned portion 127 which is arranged to fit within rectangular openings in said segments. A flat arch shaped plate 128 is arranged to fit against the type 126 and to hold their laterally turned portions in engagement with said notches and openings respectively. Reading from the upper edge of the type carrying portion of the segment, the type carried thereby read in sequence, the 10 first type being zero, the next "1" the next "2" etc., the last type on the segment being numbered "9."

A description of the operation of the stop pins, the reciprocating rack bars and the oscillating type segments will now be given. 15 In the position shown in Fig. 2 all of the stop pins 14 are down and all of the naught stops 16 are in raised position. When the stop pins 14 are in their initial raised position the vertical walls 105' of the abutment 104' fit within the notches 38 in the upper end of the naught stops and consequently holds the bars 82 and their associated bars 86 in their extreme rearward position, and 20 also retain all of the type segments in a position to print ciphers. Although each spring 91 is exerting tension to lift the bars 86 nevertheless this bar is held to the limit of its downward movement due to the fact 25 that the rest 103 carried by one end of the bell crank lever 97 will rest on top of the naught stop 16 which holds the said bell crank 97 at the limit of its downward movement by means of the pin 98 carried by the 30 member 82 and the slot 99 in the bar 86. As soon as any of the stop pins 14 are raised by means of said pin extensions, actuated by means of a card passing through the machine, the naught stop 16 in that row is lowered simultaneously, as has been heretofore explained. The downward movement of the naught stop 16 frees the abutment 104' permitting the bar 82 to be carried forward. Simultaneously with the disengagement of the abutment 104' and the stop pin 16, the 40 lever 86 is raised by means of the spring 91 which in its upward movement moves the notch 88 to fit against the front side of the reciprocating bar 89. When the parts are in their normal position, the bar 89 is at the limit of its rearward movement and rests against the vertical wall 105 of the abutment 104. As soon as the notch 88 engages the reciprocating bar 89, the said bar is 45 locked between it and said vertical wall 105 so that when the said bar 89 is reciprocated by means of the lever 114 and its associated parts, heretofore described, the bars 82 and 86 will also be moved forward. Simultaneous with the forward movement of the bar 86 the bell crank 97 is moved downward. 50 As the bar 89 is reciprocated by the lever 114, the said bars 82 and 86 will be carried with it until the cam face 101 of the bell crank engages the rectangular abutment 19

of the stop pin 14 which has been raised. This contact lifts the bell crank 97, and lowers the rod 86 against the tension of the spring 91 which in its downward movement releases the reciprocating bar 89. As soon as the bell crank 97 has been raised the vertical wall 105' of the abutment 104' will engage the rear end of the raised stop pin 14 and prevent the bar 82 from moving further. Since the reciprocating bar 89 is released as the bar 82 is stopped, the bar 89 will continue its forward movement although the bar 82 and the lever 86 have been stopped. This is for the purpose of freeing the bars 82 and 86 from the reciprocating member 89 70 as they engage the stop pins in their forward position and thereby permitting the bar 89 to carry all of the bars 86 forward which have not been freed therefrom in the manner heretofore described. 75

80 Due to the rack teeth 119, as the bar 82 is moved forward, the type segment 122 is oscillated through the medium of the gear wheel 120 as heretofore described.

85 After all of the type segments have been set by the stop pins in position to print data transferred thereto from the cards, means is provided for locking and alining the type segments so that they may not move during the printing operation. This locking and alining means will now be briefly described.

90 The extreme upper end of the lever 72 is provided with a knife shaped transversely extending arm 130 slidably mounted within a slot 131, within the cheek plates 34. Both the slot 131 and the knife shaped member 130 which is herein termed a detent, are arranged radial to the gear teeth 123 of the type segments and lock the said segments from moving, and line up the type carried 95 thereby. The locking of the printing segments and the releasing of the stops 14, is brought about simultaneously so that the reciprocating members may be free to be moved back to their original position after 100 printing without engaging any stop pins whatever except the naught stops 16. A mechanism is provided for preventing all of the ciphers to the left of the digit last set up by the stop pin from being printed. Or in 105 other words, a mechanism is provided for retracting all of the segments out of printing position which have been left against the naught stops as the released bars 82 start on their forward movement. Since this 110 mechanism is described in said co-pending application and does not directly relate to the non-print of items that are accumulated, a description thereof is not given here. The parts 132, 139 and 183 relate to this mechanism. 115

120 Means is provided for lowering the bars 86 so as to raise the bell cranks 97 so that when the bars reach the limit of the rearward stroke the rest 103 will be in position 125 130

to rest upon the top of the naught stops which are in their raised position as shown in Fig. 3.

The means for lowering the bars 86 and 5 lifting the bell cranks comprises a transverse bar 163 (Fig. 2) which is arranged above the upper edge of the bars 86 being rigidly carried by the upper ends of slide levers 164 arranged adjacent to the inner 10 face of each cheek plate 34, which, during their downward movement, slide the bar 163 in slots 165 made in the said cheek plates. The slots 165 are of a length sufficient to permit the bar 163 to move down in contact 15 with the upper edge of the bars 86 and force them downward. The lower ends of the levers 164 are provided with pins 166 which project through slots 167 in the cheek plates 34 and 35. The levers 164 are reciprocated 20 up and down by means of levers 168 arranged adjacent to the inner face of the cheek plates 34 and have bifurcated rear ends 169 which straddle the pins 166. The levers 168 are pivoted at 170 to each cheek 25 plate 34 and are oscillated by suitable connecting mechanism driven from a cam on the shaft 74.

The accumulating elements of the machine are arranged to be operated during the rearward movement of the bars 82. A description 30 of this mechanism is given in detail in said co-pending application; and may, therefore, be only briefly mentioned herein.

The accumulating mechanism comprises 35 a reciprocating carriage having spaced vertically arranged cheek plates 189, which are arranged within and adjacent to the cheek plates 34 respectively as is shown in Fig. 2. At the lower part of the forward end of the 40 cheek plates 189 is mounted a transverse horizontally extending shaft 192, the outer ends of the shaft 192 projecting through longitudinal slots 193 (Fig. 1) in the cheek plates 34. Upon the shaft 192 are mounted 45 spacing collars which are rigidly held together between the cheek plates 191 by means of collars 194 which clamps against the outside of the cheek plate 191 by means of a nut 195. Revolubly mounted in each 50 of the spacing collars are gear wheels 197 each having ten gear teeth 198 thereon. One side face of each of the gear wheels 197 is provided with an annular collar 199 having on its periphery an abutment 200 providing 55 a radial face 201 and an inclined cam face 202. The abutment 200 is made on the periphery of the collar 199 so that it lies adjacent gear tooth "0" of the gear teeth 198. The collars 199 are also provided with an 60 abutment 203 having a rounded face, and this abutment is arranged adjacent gear tooth "5" and diametrically opposite the abutment 200. The functions of the abutments 200 and 203 will be hereinafter set 65 forth.

The rear end of the cheek plates 189 are provided with longitudinal slots 205 which receive a guide rod 206 rigidly carried by the cheek plates 34 and 35.

Means are provided for reciprocating the 70 accumulating carriage backward and forward on the guide rod 206 and the shaft 192 which carries the accumulating gear wheels. This means comprises levers 207 (Figs. 1 and 3) which have their upper ends 75 209 respectively supporting the shaft 192. The lower ends of the levers 207 are pivoted to stud shafts 211 carried by levers 215 which have horizontally extending portions 217 (Figs. 4 and 5) which extend inwardly 80 toward each other and are provided with vertically extending relatively rectangular shaped plates 219 pinned together at their upper and lower ends by means of pins 221. The said plates 219 are provided with registered openings 223 and 224 to receive a cam shaft 225, loosely mounted on a shaft 226 which passes through its center. Rigidly mounted upon the shaft 226 are collars 227 and 228 (Fig. 3) which abut against the 90 ends of the cam shaft 225 and are held in locked position by means of set screws 229. The collar 227 is provided with an annular groove 230 to receive the bifurcated end 231 (Fig. 2) of a lever 232 which is pivotally 95 mounted at 233 to the frame work 234.

The base 10 carries the entire typesetting and accumulating mechanism and also the reciprocating printing carriage 13. The lever 232 intermediate its ends is provided 100 with a rectangular cage 235 within the walls of which is reciprocatably mounted a plunger 236 having a cam engaging head on its upper end. A spring 237 is compressed between the inner face of the said cam engaging head and the wall of the rectangular cage. The spring is normally held compressed by means of a bell crank 238 pivoted to the lever 232, one end 239 of which is adapted to engage a collar 241 carried on the inner end of the reciprocating plunger 236. The other arm of the bell crank 238 upon being pressed, disengages the end 239 from the collar 241 and permits the plunger 110 to be forced upwardly under action of the spring, whereupon the plunger enters a spiral cam groove 244 (Fig. 6) in the periphery of the cam 77. As the cam head runs in the groove 244 the lever 232 will be pushed to one side by the said groove and thereby cause a sidewise movement of the lever 232 which will slide the cam shaft 225, for a purpose to be hereinafter set forth. As the cam reaches the end of its revolution, an abutment 245 secured therein and having an inclined face 246 will engage the end of the plunger head and force it downwardly, whereupon the collar 241 snaps in back of the said lever 238 and is held in its locked position (Fig. 2). A coil spring 248, 120 125 130

strained between the end of the lever 238 and the upper edge of the lever 232, normally holds said end in an upward position to be engaged by the collar 241. The levers 207 and 208, as before described, are for reciprocating the accumulating carriage. These levers are pivotally mounted upon a transverse shaft 250 which is mounted in the cheek plates 34. Between the said levers 207 and 208, as before described, are the inner contacting ends 251 of levers 253 and 254 respectively which have openings 255 and 256 to receive the cam shaft 225. Near their inner ends, the levers 253 and 254 are provided with offsets 257 whereby the parts that receive the cam shaft 225 are spaced apart. The outer ends of the levers 253 and 254 have upwardly turned portions provided with revolvably mounted rollers 258 and 259 respectively. The roller 259 is adapted to run in a cam groove 260 in the cam 118 which, during the revolution of the said cam, transmits a rocking motion to the lever 254 which through the medium of the levers 215 and 207 reciprocates the accumulating carriage. When the said accumulating carriage is being reciprocated by the lever 254, the accumulating elements thereof are actuated for accumulating purposes only, as will be hereinafter more fully explained, and consequently the lever 254 may be termed the "accumulating lever". A coil spring 263 is strained between ears 264 carried by the lever 207 the lever 215 for the purpose of normally holding a lug 266 carried by the lower edge of the lever 207 against the lower edge of an opening 267 made in the upper end of the lever 215. The springs 263 are of such strength that the levers 207 and 215 are for all practical purposes, as though they were made as a single lever.

The roller 258 is revolvably mounted in a cam groove 268 of a cam 269 which, during the revolution thereof, will transmit a rocking motion to the lever 253, which motion, through the medium of levers 207, will reciprocate the accumulating carriage. Since the reciprocating carriage is reciprocated by the levers 253 only when taking the total this lever 253 may be termed the "total taking lever."

The cam shaft 225 is provided with an annular groove 271 having inclined side walls 272 and 273 respectively. The openings 223 and 224 form bearings for the cam shaft 225. The groove 271 is of a width greater than the space between the levers 253 and 254 so that only one of the said levers at a time can have the walls of its opening 255 or 256 in contact with the periphery of the cam shaft 225. As for instance, when the cam shaft is shifted by the lever 232 and its associated parts, as heretofore described, and the levers 253 has the walls of its open-

ing 273 in engagement with the periphery of the cam shaft 225, the opening 256 in the lever 254 will not engage the periphery of the cam shaft 225 but will be free within the groove 271 (Fig. 5). When the cam shaft 225 is shifted in the reverse direction, the levers 253 and 254 occupy the position shown in Fig. 4, in which case the lever 253 is shown loosely mounted in the groove 271 while the edges of the opening of the lever 254 are in engagement with the periphery of the cam shaft. Since both of the levers 253 and 254 are always being oscillated through the action of their lever which is loosely mounted in the groove 271 it may frequently not be in a position where its opening will exactly register to receive the cam shaft 225 when it is moved sidewise. Due to the inclined walls 272 and 273 of the annular groove 271, however, when the cam shaft 225 is moved sidewise in the opening in one of the levers 253 or 254, the edges of the said opening will slide upon the inclined walls of the annular groove 271 until they come in position to receive the cam shaft. When the cam shaft is moved sidewise so as to place the edges of the opening of the levers 253 or 254 in engagement with the periphery of the cam shaft, a positive connection will be made between the said lever and its cooperating levers 215 and the accumulating carriage reciprocated. At this time the other lever whose opening is loose in the groove 271 has no operative effect on its associated lever 207 for reciprocating the accumulating carriage. From the above it is apparent that the levers 253 and 254 are selectively locked, so to speak, to the cam shaft 225 for reciprocating the accumulating carriage, the lock and release being actuated by the shifting of the cam shaft 225.

The purpose of the different cycles of the reciprocation of the accumulating carriage by two different levers, and its effect upon the accumulating and printing mechanisms will be hereinafter explained.

Now will be considered the position of the parts in which the lever 254 is locked on the cam shaft 225 and the accumulating carriage is being reciprocated thereby for the purpose of accumulating. At this time the elements of the accumulating mechanism occupy the position shown in Fig. 2.

As is shown in this figure, the printing operation has been completed, and the other elements of the printing mechanism have been so set to permit a free passage of the reciprocating members 82 in a rearward direction. Before the members 82 move rearwardly however, the lever 254 is operated which will reciprocate the accumulating carriage forwardly until the accumulator wheels 197 have been brought into contact with the gear teeth 123 of the type seg- 130

ments. The rearward movement of the bars 82 will then rotate the accumulating gear wheels 197 and turn the teeth thereon to an extent which corresponds with the type last 5 set up by the type segments.

When the rack bars 82 have reached the limit of their rearward movement, the lever 254 is again rocked to reciprocate the accumulating carriage rearwardly and there- 10 by disengage the accumulating gear wheels with the gear teeth of the type segments, and bring the said accumulating gear wheels into engagement with a transverse bar 272 which is carried by the cheek plates 34 and 15 holds the said accumulating gear wheels against accidental shifting.

This reciprocation of the accumulating carriage backward and forward and the engagement and disengagement of the accumulating gear wheels with the gear teeth of the type segments takes place as the bars 82 are at rest.

However, when any of the accumulating gear wheels have made a complete revolution 25 the inclined wall 202 (Fig. 2) of the abutment 200 carried by the said gear wheel has been brought into engagement with the inclined wall 273 made on the lower end 274 of an L shaped lever 275, the said lever 30 is rocked upwardly on its pivot 276 against the action of a coil spring 277 strained between the lever 275 and a transverse rod 276 carried between the cheek plates 189, normally holds the lever 275 in a horizontal 35 position. In its horizontal position, the lever 275 holds a vertically extending lever 278 to the limit of its upward movement, the upper edge of the lever 275 engaging a lip 279 carried by the side of the lever 275 40 to hold it in its said upward position against the tension of a coil spring 280 strained between the said lever and a transverse rod 281 carried between the cheek plates 189. A horizontally disposed comb plate 281' is carried between the cheek plates 189 forms guideways for the vertical extending levers 278. Pivoted to the lower 45 end of the lever 278 is a horizontal lever 283 which is pivotally connected to the lower end of a lever 285 which is provided 50 with an enlarged slot 286 receiving the transverse shaft 276. The upper end of the lever 285 is shaped to form a lever 287 which 55 extends rearwardly in a relatively horizontal direction and is pivotally mounted upon a transverse rod 289. A spring 290 carried between the lever 285 and a transverse rod 291 carried by the cheek plates 189 normally 60 holds the outer end of the lever 287 in a downward position. The said outer end of the lever 287 is slidably mounted in a comb plate 292 and carries on its outer end a rev- 65 olubly mounted roller 294 adapted to engage a stepped cam plate 295 provided with cam surfaces 295' which plate is recipro-

cated back and forth for lifting the roller 294 and rocking the lever 287 against the tension of the spring 290. The cam plate 295 is disposed between the cheek plates 34 and carries at its side edges rollers 296 70 which are adapted to roll in longitudinal slots 297 (Fig. 1) in the cheek plates 34.

The means for reciprocating the cam plate 295 backward and forward comprises levers 298 pivoted to the cam plate at the point 299, and carry on their lower edges teeth 300 which mesh with a pinion 301, revolubly mounted upon a shaft 302 slidably mounted in a longitudinal slot 303 in the cheek plates 34. 80

The shaft 302 is moved backward and forward in a slot 303 by means of a lever 307 which has a bifurcated upper end 308 fulcrumed on stud shafts 309 carried by the cheek plates 34. The lower ends of the levers 307 are bifurcated as at 310 to straddle a transverse shaft 311 reciprocated in parallel slots 312 (Fig. 1) in the frame work 234. The transverse shaft 311 passes through the entire machine and is arranged to receive the levers 307 of each independent unit or zone. Levers 313 arranged on each side of the machine have one end 314 pivotally mounted on the transverse shaft 311 and their other ends provided with a longitudinal slot 315 to receive the main drive shaft 74. This end of each lever 313 is provided with a revolubly mounted roller 318 which is arranged to rotate in a cam groove 319 in the cam 77. 90 As the main shaft 74 is revolved, through the lever connections heretofore described, the stepped cam plate 295 is reciprocated back and forth. Due to the arrangement of the pinion 306 and the rack bars 298 and 305, the movement of the rack bar 298 is 95 in ratio of two to one to the movement of the pinion 306 on the rack bar 305. 100

Returning now to the L shaped lever 275, it will be seen that means is provided for locking the rear end of this lever in a downward position when the vertical portion 275 thereof has been raised by engagement with the abutment 200 carried by the accumulative gear wheels. This means comprises a bell crank lever 320 (Fig. 2) pivoted upon a transverse shaft 321 carried by the cheek plates 169. Horizontally disposed comb plates 322 guide these levers during their movement. A coil spring 324 strained between the upper end of the lever 320 and a transverse shaft 325 carried by the cheek plates 189 will normally pull the upper end of the lever 320 forwardly and hold it against the inner end of the lever 275. When the lower end of the lever 275 is raised as heretofore described, the vertically extending portion 326 thereof will snap within a notch 327 formed in the front edge of the lever 320 and hold the said portion 326 in its downward position. The other 110 115 120 125 130

- arm 328 of the bell crank 320 is adapted to come in contact with the transverse shaft 206 and upon doing so will move the upper end of the lever rearwardly against the tension of the spring 325 releasing the vertically extending portion 336 of the lever 275 from the notch 327 and permit the said lever 275 to occupy its horizontal position under the action of the spring 277.
- 10 A description of the operation of the carry over mechanism which has just been above described will now be given. After the accumulating gear wheels have made a complete revolution and the abutment 200 thereon comes in contact with the cam face 273 of the vertically extending portion 274 of the lever 275 the said lever will be rocked about its pivot so that its inner end is lowered. The lowering of the inner end of 20 the lever 275 permits the vertically extending rod 278 to be drawn down under action of the spring 280 so that the lever 283 will be dropped down in front of the abutment 104 carried by the reciprocating bars 82.
- 25 When any one of the accumulating gear wheels has made a complete revolution the reciprocating bar 82 associated therewith will of necessity be in its extreme rearward position. Both the vertically extending lever 278 and the inner end of the lever 275 descend simultaneously, the lever 275 being locked in its downward position by means of the bell crank 320 and the vertical lever 278 being held in its downward position by 30 means of the coil spring 280. When the parts are in the position above described, the reciprocating cam plate 295 is moved forwardly by means of the levers 298, 307 and their associated elements. A forward movement of the cam plate 295 will engage the inclined cam surface 295' thereon with the roller 294 carried by the inner end of the lever 297 thus raising the roller. The lifting of the roller 294 will rock the lever 285 about its pivot 288 thereby forcing the lever 283 pivoted thereto in a rearward direction and bringing the inner end of the lever 283 into engagement with the abutment 104 made on the upper edge of the reciprocating bar 82, and force the said bar backward a distance sufficient to turn the gear wheel 120 to oscillate the type segment a distance sufficient to rotate back one tooth distance, the accumulator gear wheel with which it 45 is associated. Due to the fact that the abutments 200 are carried by the left hand face of each accumulative gear wheel, the set back mechanism heretofore described of the next adjacent accumulative gear wheel to 50 the left is actuated. In other words, a rotation of one of the accumulative gear wheels will actuate the set back mechanism of the accumulative gear wheel of the next higher order.

- 63 A brief description of the entire machine

thus far described will now be given explaining the sequence of operation of the various mechanisms to print and accumulate the data perforated in the cards which are passed through the machine.

As a card is fed through the machine various stop pins 14 are elevated corresponding with the various perforations of the card. The elevation of the stop pins 14 will lower the naught stops 16 in the rows in which the stop pins are elevated. The lowering of the stop pins will permit the reciprocating bars 82 associated therewith, and these levers will depress all of the levers 132 to the right thereof which have not been depressed by the forward movement of the reciprocating bars associated therewith. All of the levers 132 however, to the left of the lever 132 which has been depressed by the forward movement of the rack bar will still be in their upright position. While the reciprocating bars 82 which have been released are moving forwardly, these last mentioned levers 132 will be reciprocated rearwardly by means of the bell cranks 139 levers 143 and other elements associated therewith, which in their rearward movement will force back the bars 82 with which they are associated, and oscillate the type segments actuated by these rack bars downwardly to a non-print position. The bars 82 move forwardly under the action of the reciprocating bar 89 until the abutments 104 carried on their lower edges come in contact with the various elevated stop pins 14 at which time they come to a rest. When the rack bars 82 have come to a rest, the segments associated therewith have been oscillated upwardly a distance sufficient to set the type thereon in consonance with the number of the stop pin 14. When all of the type segments have been oscillated into proper position the detent 130 is drawn down into engagement with the gear teeth 123 on the type segments and alines and locks them so that they cannot be moved during the print operation. Simultaneous with the operation of the detent, the levers 62 and 163 are actuated, the former causing the drawing down of the set stop pins 14 and elevating all of the naught stops 16, the latter contacting with the reciprocating bars 86 for lowering them so that on their return movement the bell cranks 97 carried thereby will be in position to rest upon the top of the naught stops 16. The reciprocating printing carriage 13 is then brought into engagement with the type segment and an impression made on the paper carried thereby. The rack bars 82 are now ready for their rearward movement, but previous thereto the reciprocating accumulating carriage has been moved forwardly so that the accumulating gear wheels are brought into engagement with the teeth 123 of the type segments. The locking detent 130

for the type segments is withdrawn and the reciprocating bars moved rearwardly under action of the bar 89. The rearward movement of the rack bars 82 will revolve the accumulating gear wheel through the medium of the type segments and rotate the gear teeth thereon corresponding with the type printed. When the bars 82 have completed their rearward motion, the reciprocating accumulating carriage is also moved rearwardly so as to disengage the accumulative gear wheel from the type segments and to move them into engagement with a transverse bar to lock them against further rotation. All of the elements are now ready for a second forward movement of the reciprocating bars 82, and the above operation continues. When any of the accumulative gear wheels have made a complete revolution, during which time the bars 82 associated therewith have moved rearwardly into naught stop position, the L shaped bars 275 are rocked, which through the mechanism heretofore described, will move the rack bar 82 adjacent to the left thereof, back one space so that the accumulative gear wheel associated with this rack bar will also be moved back one space, and in this way form the "carry over."

The above operation continues as the cards pass through the machine and the items thereon are printed by the type sectors and accumulated on the accumulator wheels until either a total card is fed to the machine or until it is desired to take the total of the data accumulated by operating a total key manually. A description of this total taking mechanism will now be given.

All of the actions heretofore described have taken place when the lever 253, which I term the "accumulating lever", is locked by means of the reciprocating cam shaft, to the levers 215. When the total is to be taken the key 240 is lifted either manually or by a push rod A controlled by the perforated cards, as is described in my co-pending application, Serial No. 80,973, filed Feb. 28, 1916. The reciprocating plunger 238 is released, which will spring into the cam groove 244 and upon engaging therewith will rock the lever 232 about its pivot 233 and reciprocate the cam shaft 255 to the position shown in Fig. 5, which will unlock the accumulating lever 253 and lock the total taking lever 254, whereupon the locking of the levers 207 with the other lever 253 will cause the said lever to reciprocate the accumulating carriage forwardly until the accumulator wheels are brought into contact with the type segments.

At the same time that the cam shaft 255 is reciprocated as above described, means is provided for lowering the pins 14 and the naught stops 16 so that the bars 82 will be in a position to move forward. This

means is described in detail in said co-pending application Serial No. 158,142 and need not be described here.

After the accumulator gear wheels have been moved into mesh with the gear teeth 70 on the type segments and after both the naught stops and the stop pins have been lowered as above described, all the elements will have been set to permit a forward movement of the bars 82. The bars 82 are 75 moved forward under the action of the transverse bar 89 and its associated elements, the said bar 89 being gripped between the abutments 104 and the notches 88 formed in the upper edges of the bars 80 86. The forward movement of the bars 82 rotate the accumulator gear wheels in the direction which is anti-clockwise in Fig. 2, until the radial wall of the abutments 200 come into contact with the rear edges of 85 90 the vertically extending portion of the bar 275. When the accumulating gear wheels have been stopped in the manner heretofore described they have revolved their associated type segments upwardly a distance sufficient 95 to set into printing position the type corresponding with the gear teeth of the accumulating wheels. Since all of the accumulating wheels will not revolve the same distance, but since it is necessary that the bar 89 should move to the limit of its outward movement, means is provided for releasing the said bar from engagement with the notches 88 formed in the bar 86 so that the bar 89 may slide on the upper edge 100 of the bar 86 as is shown in Fig. 26. This means comprises a lever 350 pivoted to a transverse shaft 351 carried by the cheek plates 189, and is provided on its upper edge with a rounded abutment 353 which is adapted to come in contact with the rounded abutment 203 carried on the collar 199. When the said abutment 203 and 353 come into said contact, the lever 350 is forced downwardly, which will force the bars 86 105 110 also downwardly through the medium of an outwardly turned lip 354 formed on the outer end of the lever 350. The forcing down of the bar 86 as before described, will release the transverse reciprocating bar 89 and permit it to move downwardly to the limit of its stroke. When all of the type segments have been set up in the manner heretofore described, the detent 130 is 115 120 brought into contact with the gear teeth of the type segments and locks the said segments in printing position. The reciprocating printing carriage 13 is then moved up into engagement with the type and an impression made on the paper carried thereby. This impression gives the total of the data accumulated by the accumulative gear wheels. After the printing operation is completed the detent 130 is lifted. The bar 82 then move rearwardly during which 125 130

motion, the reciprocating plunger 238 is forced back into its locked position as shown in Fig. 2, and the lever 232 has been rocked about its pivot 233 and thereby reciprocated 5 the cam shaft 225 back to accumulating. All of the parts are now in the position to accumulate further data.

It is to be understood that all the description thus far has been given relative to the 10 operation of one unit of the machine, that is, one printing and accumulating section composed of 9 type sectors and 9 accumulating gear wheels together with their associated and cooperate elements. It is also 15 to be understood, however, that each unit may contain a greater or less number of associated printing and accumulated elements. The complete machine, however, comprises a number of units each identical 20 with the unit heretofore described. Means is provided for holding the bars 82, associated with the digits to be kept from printing and accumulating, so that it cannot run forward and backward to set type 25 and accumulate and also to hold the bar 82 back far enough to render the type segment associated therewith to occupy a non-print position. This means comprises a plurality of latch levers 401 (Fig. 2) which 30 are pivotally mounted upon a transverse bar 402 carried between the cheek plates 34 of the machine. When it is desired to render a line of digits inoperative, the reciprocating bar 82 associating therewith is 35 drawn back so that the upper end of the latch lever 401, which is provided with a hook 403 will hook over a horizontally extending pin 404 carried by the vertically extending portion 92 carried by the bar 82.

40 The printing carriage, designated generally by reference numeral (Figs. 1 and 7) is located on the printer tabulator base, opposite the type 126.

45 The carriage is supported at opposite ends on the cam shaft brackets 599 and the lever shaft brackets 601 carried on the base plate of the printer tabulator. These brackets are tied together at their upper part by the tie plates 602 bolted at opposite ends 50 to the upper part of these brackets respectively.

55 The lever shaft brackets 601 are provided at their upper ends with guide slots 604 in which are received the L shaped carriage supporting brackets 605 provided at their forward ends with anti-friction rollers 606 adapted to reciprocate in the elongated openings 607.

60 The supporting brackets 605 are formed near their rear ends with uprights 608 between the upper ends of which are carried the rail supporting bar 609. Between the rear ends of said supporting brackets is carried the arm supporting shaft 610, intermediately of the ends of which are car-

ried the L shaped supported members 612 comprising the forwardly extending carriage supporting arms 614.

Intermediately of the ends of the supporting bar 609 are carried the forwardly 70 projecting plates 615 which carry at their forward ends the carriage rail 616.

The brackets 605, the bar 609, the shaft 610, the supporting member 612 and the rail 616 together form a structure which 75 may be called the reciprocatory or movable support for the carriage proper.

The carriage proper comprises end plates 80 616 held spaced apart by the tie rod 613 and the bracket shafts 629. On the bracket 85 shafts are mounted the rearwardly extending supporting brackets 618 each provided with a circular opening adapted to receive the carriage rail 616, this opening being provided with a rearwardly extending slot 614 adapted to provide a passage for the tie plates 615 when the carriage is slipped on to the carriage rail. When the carriage 90 has been put in place it is thus supported by said carriage rails and by the forward ends of the arms 614 engaging under the tie rod 613 at the lower forward part of the carriage.

Between the end plates 617 is mounted the 95 paper roller shaft 620 carrying part of the paper supporting and feeding mechanism to be mentioned thereafter.

The forward edge of the uprights 608 (Fig. 9) of the brackets 605 are provided with inwardly turned perforated ears 621 100 carrying supporting studs 622 on which are slidably mounted the locating bar 624 provided with elongated slots 625 receiving said studs, said bar being also provided with a plurality of holes 626 large enough to receive 105 the heads of the locating stud 627 fixed on the locating bracket 628 fixed to the bracket shafts 629 connecting the end plates 617.

The carriage may be swung outwardly upon the rail 616 (Fig. 7) until the stud 627 110 clears the holes 626, and the carriage then shifted longitudinally until the stud engages in a different hole 625, as desired. The stud 627 and bracket 628 are locked in the adjusted position by means of a locking plate 115 630 (Fig. 9) provided with key slots 631 each having a large end 632 (Fig. 8) thru which the head of the stud 627 is adapted to pass and with small ends 634 adapted to form shoulders to engage under the head of said stud whereby the stud is positioned by means of a spring 635 tensioned between the upright 608 and the angular manipulating end 636 bent outwardly on said locking plate. The locking plate is held in proper position relative to the locating bar by means of a guide plate 633 secured to an upright 608 (Fig. 9) receiving one end of the locking plate and slotted guide plate 633' secured to the other end of the locking plate 120 125 130

and embracing the screw 634' in the ear 621. The printing is accomplished by the forward movement of the paper supporting mechanism which movement brings the paper against type of the type sections. This is accomplished by means of the upper and lower carriage actuating levers 637 and 638 (Fig. 7) pivoted on the lever shaft 639 carried by lever shaft brackets 601. The upper and lower actuating levers are both pivotally mounted on said shaft 639 and when in printing position are locked together as will be explained, and are oscillated by means of the engagement of the cam roller 640 engaging in the cam groove 641 of the printing cam 642 carried on the cam shaft 74. The actuating levers give one complete cycle of oscillation once for every revolution of the cam shaft 74.

This locking is accomplished by means of locking cones 645, which are shown in unlocked position in Fig. 8 and must be moved to the right of said figure to lock said upper and lower levers against relative movement. These cones engage in, and when locked, hold in alignment the openings 648 and 649 of said upper and lower levers, and are carried on the cone supporting shaft 650 yieldably drawn to unlocked position by means of the tension spring 651 secured between the end of said shaft and across piece 652 disposed across the opening 654 (Fig. 7) in the lever bracket 601. The opening 654 is large enough for the insertion of the cone shaft and cones when assembling the machine.

These cones may be moved to locking position by means of the bell crank lever 655 fulcrumed on the base of the machine and provided at its upper end with spaced ears 656 engaging a transverse pin 657 in the cone supporting shaft 650. This lever is actuated by means of a link 658 pivoted at its lower end to the motive arm of said lever, and at its upper end to the locking lever 660 (Figs. 2 and 7) fulcrumed intermediately as at 661 on the cam shaft bracket 599. The locking lever 660 terminates in a manipulating end 662 (Fig. 1) received in a slot 664 of the locking plate 665, said slot being provided at its upper and lower parts with shoulder forming recesses 666 and 667 in which said manipulating end may be locked to retain said locking cones in either locked or unlocked position.

On the paper roller shaft 620 journaled in the end plates 617 (Figs. 6 and 7) are disposed a plurality of paper rollers 748. Between adjacent pairs of the paper rollers and loosely engaging said bushings are carried the elastic platen block 758 of rubber or other suitable material.

Partly surrounding or housing the lower part of the paper rollers 748 are the outer paper shields 780 (Fig. 8). These outer

shields cooperate with the paper rolls to form guides for the paper 871 (Fig. 7) on which the tabulations are to be printed, said outer shields being continued upwardly in front of the paper rollers 748, whereby are formed extensions 784 (Fig. 8) between which the type of the type sectors pass when the paper is pressed against them by means of the platen blocks 758.

After each number is printed by the type of the type sectors, it is necessary to feed the paper upwardly one or more spaces. This feeding is accomplished by means of engagement of the teeth of the feed ratchet 801, mounted on the shaft 620, by a suitable feed pawl 802 (Fig. 7) pivotally mounted as at 803 on the feed pawl lever 804 fulcrumed intermediately as on the stud shaft 805 and driven by the link 806, in turn driven by the drive lever 807 mounted on the feed shaft 808, said shaft being actuated by the actuating arm 809 fixed on said shaft and adapted to come into contact with and be moved by the abutment shaft 810 carried on the abutment shaft brackets 811 pivotally mounted on the tie plates 602. As the feed pawl is described in said co-pending application and forms no part of the present invention, it need not be described here. The brackets 811 are limited in their rearward movement by the engagement, with the tie plates, of a shoulder 812 formed by the lower edge of the lug 814 laterally turned at the rear edge of said abutment shaft brackets, and is yieldably held at its rearward limit of movement by a spring 815 tensioned between said lug and a lug on the rear part of the shaft tie plate 602.

When the carriage is moved forwardly toward the type sectors the free end faces 816 of the actuating arm 809 engage and push down the abutment shaft 810 against the action of the spring 815 until said end face clears said shaft and permits the shaft and its bracket to be snapped back by the spring 815 until stopped by the shoulder 812.

After the printing has taken place and the carriage moves rearwardly, the abutment shaft 810 is engaged by the lower side of the actuating arm 809 whereby said arm and drive lever 807 are raised thus rocking the pawl lever 804 and lowering the pawl 802, thus turning the ratchet 801 one or more teeth.

The feeding mechanism is yieldably held in position to feed by means of a spring 825 tensioned between the end plate 617 and a perforated ear on the upper part of the inner end of the arm 807.

When it is desired to insert, remove or feed the paper entirely independently of the feeding mechanism just described, I provide a mechanism comprising the paper feed gear 829 (Fig. 8) fixed on the paper

feed shaft 620 and engaged by the idler gear 830 rotatably mounted on the end plate 617, the idler gear being in turn engaged by the knob gear 831 fixed on the stud shaft 805 rotatably mounted in the end plate 617 and carrying knurled knob 832 by which said shaft and gears may be manually rotated.

While the paper is being fed and during the time of printing, it is desirable that it be firmly held against the platens. This is accomplished by means of a clamping mechanism comprising a clamp bar 833 (Fig. 7) carried between the outer ends of the clamp levers 834 provided with intermediate longitudinal slots 835 loosely receiving the paper feed shaft 620, whereby the paper clamp bar is adapted to move toward and from the paper rollers as well as to revolve with said rollers. The inner ends of the clamp levers are provided with small pins 836 received in longitudinal slots 837 in the lower ends of the spring levers 838 intermediately fulcrumed on the end plates 617 and drawn by a spring 839 strained between the upper end of the spring levers and the upper part of end plates 617, whereby the clamp lever 834 is yieldably drawn downwardly and the clamp bar 833 yieldably pressed against the paper and presses the paper against the paper rolls 748.

This yieldable engagement maintains during the printing and feeding of the paper, but after feeding has taken place, as above described, the releasing pin 840 mounted on the cam bracket shaft 841 comes into contact with the abutment shaft 810 and forces the cam bracket shaft and the cam bracket 842 to rock rearwardly whereupon the cam edge 843 forces outwardly the pin 836 and therewith the lever 834 and bar 833 and also rocks said lever in a direction clockwise on Fig. 7 whereupon the bar 833 is moved downwardly over the paper and later takes a fresh grip upon the paper when the clamping lever is released by the cam on the next forward movement of the carriage and moves downwardly under the action of the spring 839.

I prefer to use an inking ribbon of which the supporting and feeding means is generally indicated by reference numeral 850, but this forms no part of the invention herein claimed.

When a total is printed it is desirable to show some visual signal to indicate that the number printed is a total. This is accomplished by shifting the carriage to the left when the total is printed, whereby the total is shown printed a little into the right of the alignment of the listed column.

Means for accomplishing this result will now be described.

As shown in Fig. 8, the lower edge of

the locating bar 624 is provided with a notch 880 in which engages the upper end of the vertical lever 881 pivoted intermediately on the bracket 882 fixed on the printing lever shaft 639 the lower end of said lever being pivotally connected to the rear end of the horizontal lever 884 pivotally connected to the rear end of the horizontal lever 884 (Fig. 6) intermediately pivoted on a pin 885 in a lug 886 on the base of the machine. The forward end of said horizontal lever is pivotally connected to the rear end of the total shift lever 232.

When the total pin 236 engages in the groove 244, said pin is shifted to the right, and the upper end of the lever 882 is, therefore, shifted to the left, whereupon the locating bar is moved to the left on the pin 622 in the slot 625, thus causing the printing to take place a slight distance to the right of the column.

When by means of the lever 660 the carriage has been set to a non-printing position so that the items accumulated are not printed, it is still desirable that the totals themselves be printed. In order to accomplish this printing automatically, there is provided the automatic printing lock lever 887 (Fig. 8) pivotally mounted on the bracket 888 fixed to the shaft 639, the upper end of which lever engages in a notch 890 the lower end engaging a transverse pin 891 in the printing lock shaft 650. When the carriage is shifted to the left, the bar 624 is moved therewith and carries the upper end of the lever 887 to the left whereupon the lower part of said lever, said printing lock shaft and the cones 745 are moved to the right thus locking together the upper and lower printing levers 637 and 638 and effecting the printing.

From the foregoing, the operation of the printing carriage will be easily understood. Paper is inserted in the rear opening between the outer shields 767 and the paper rolls 748, and the paper rolls 748 are turned by means of the knob 431 until the part on which it is desired first to print are opposite the platen blocks 758.

The locking lever 660 is set in locked or unlocked position depending upon whether it is desired that the items be printed or not.

The machine is then started in operation as heretofore explained and the type is set and the accumulators accumulate. If the locking lever is set in locked position the cams 642 cause the printing levers and the carriage to reciprocate and the printing is effected.

When a total is taken the carriage is moved to the left just before the printing by means of the total signal lever 881 engaging in the notch 880 of the locating bar. If the locking lever 660 has not been set in printing position, the automatic levers 887 also cause the cones 745 to lock the printing levers and

print totals when the totals are set up and presented by the type sectors.

I claim as my invention:

1. In an apparatus of the character described, the combination of an accounting machine provided with type and an accumulator; means for operating the accumulator to take totals or to accumulate; a carriage for pressing paper against the type; means operating said carriage; means for rendering the carriage operating means operative or inoperative; and means for controlling the carriage operating means and the accumulator operating means for causing the carriage to operate when the accumulator takes totals.

2. In an apparatus of the character described, the combination of a carriage; a pair of levers each comprising two parts having openings adapted to be alined with each other; means operatively connecting the carriage to one of said parts of each pair; means for reciprocating the other of said parts; cones adapted to be passed thru said openings when said openings are alined with each other to lock said parts together; a cone shaft for holding said cones in alinement with each other; a spring engaging said cone shaft for drawing said cones into unlocked position; and levers engaging said shaft for moving said cones into locked position.

3. In an apparatus of the character described, the combination of a paper carrying carriage; type setting means for listing and for setting up totals; means cooperating with said carriage and type setting means for effecting printing; means for rendering the printing effecting means inoperative; and means for automatically rendering said printing effecting means operative when said type setting means sets up and prints totals.

4. In an apparatus of the character described, the combination of a carriage; a pair of levers each comprising two parts; means operatively connecting the carriage to one of such parts of each lever; means for reciprocating the other of said parts of each lever; means for locking said parts of each lever together; means cooperating with the carriage for printing totals; and automatic means connecting the total printing means with the locking means for automatically locking said parts together when totals are printed.

5. In an apparatus of the character described, the combination of a carriage; a pair of levers each comprising two parts having openings therein adapted to be alined; means operatively connecting the carriage to one of said parts of each lever; means for reciprocating the other of said parts of each lever; movable means adapted to pass thru said openings when alined to lock said parts of each lever together; means

cooperating with the carriage for printing totals; and automatic means connecting the total printing means with said movable means for drawing said movable means into the openings when totals are printed.

6. In an apparatus of the character described, the combination of a carriage; levers each comprising two parts having openings adapted to be alined with each other; means operatively connecting the carriage to one of said parts of each lever and means for reciprocating the other of said parts of each lever; cones adapted to be passed thru both of said openings of each lever when the openings are in alined position; cone shafts connecting said cones; means cooperating with said carriage for printing totals; and automatic means connecting the total printing means with said shaft for automatically drawing said cones into said openings when totals are printed.

7. In an apparatus of the character described, the combination of a tabulating mechanism adapted to set type for printing items and totals; a paper carriage; means for causing relative reciprocation between said carriage and mechanism for causing printing; means for at will rendering the reciprocating means inoperative whereby printing will not be effected; and means for at will causing said mechanism to set totals and said reciprocating means to become operative.

8. In an apparatus of the character described, the combination of a tabulating mechanism adapted to set type for printing items and totals; a carriage for holding paper; means for causing said carriage to reciprocate to and from said type for causing printing; means for causing the paper to feed upwardly after each printing operation; locking means for rendering the reciprocating means operative or inoperative whereby items are printed or not printed; a shifting means for causing said mechanism to set totals; levers connecting said shifting means with said carriage whereby the carriage is shifted sidewise when totals are printed; and a lever connecting the carriage with the locking means whereby the locking means is locked to print totals.

9. In an apparatus of the character described, the combination of an accounting machine having type segments and an accumulator cooperating with the type segments; means for operating the accumulator to accumulate; means for operating the accumulator to take totals; a cam for selectively putting into operation either of said means; a carriage adapted to press paper against the type of the type segments; levers comprising sections for operating said carriage; locking cones for locking said sections together; and means for shifting said cams and said cones whereby when said cam is

- shifted to take totals said locking cones lock said segments together.
10. In combination, a mechanism for accumulating a series of items all of which 5 items may be greater than unity, and a total taking mechanism for automatically excluding the printing of items, which mechanism automatically becomes operative for printing totals.
11. In combination, a mechanism for accumulating a series of items, any of which may have more than one digit, a total taking mechanism and a printing mechanism adapted automatically to exclude the printing of 15 items and adapted to automatically become operative for printing totals.
12. In combination, an item-accumulating mechanism; a total-taking mechanism; and a printing mechanism at will settable for excluding the printing of all items and for 20 automatically becoming operative for printing totals composed of items some of which have more than one digit and thereupon automatically moving to exclude the printing of additional items.
13. In combination, an item-accumulating mechanism; a total-taking mechanism; and a printing mechanism for omitting the printing of any items at all and for automatically 25 becoming operative for printing totals.
14. In combination, an accounting machine adapted for substantially simultaneously accumulating a plurality of items of more than one digit; a total-taking mechanism for setting up the totals of said items; 30 and a printing mechanism settable to be rendered inoperative for printing of all of the items and to become automatically operative to print the totals of items of more than one digit and thereupon automatically moving to exclude the printing of additional items.
15. In combination, an accounting machine adapted for substantially simultaneously accumulating a plurality of items of more than one digit; a total-taking mechanism for setting up the totals of said items; 35 and a printing mechanism at will settable to exclude the printing of any items at all and to become automatically operative to print said totals and thereupon automatically moving to exclude the printing of additional items.
16. In combination, a mechanism adapted
- to set up statements of different kinds; a printing and paper feeding means cooperating therewith and adapted to be rendered inoperative; and means for automatically rendering the printing and paper feeding means inoperative when statements of a certain kind are set up.
17. In combination, a mechanism adapted to set up statements of different kinds; a printing and paper feeding means cooperating therewith and adapted to be rendered inoperative; and means for automatically causing said printing and paper feeding means to remain inoperative when statements of one kind are set up and to automatically become operative to print and feed when statements of another kind are set up.
18. In combination, an accounting machine adapted to accumulate items and set up totals; a printing and paper feeding means cooperating therewith; and means for causing the feeding means to remain inoperative and hold the paper from feeding when items are accumulated, and to automatically become operative to feed paper each time a total is printed.
19. In combination, an accounting machine; a printing and paper feeding means cooperating therewith and adapted to be rendered inoperative; and means for causing said machine to set up totals and for constraining the printing and paper feeding means to remain inoperative when items are set up and to automatically become operative to print totals and feed paper when totals are set up.
20. In combination, a tabulating mechanism adapted to set up items and totals; a paper carriage; a support for said carriage reciprocatory to and from said type; means for causing the paper to feed an increment between successive printings; settable means for causing the carriage support to remain idle when items are accumulated and means adapted both to cause the carriage support to move to print totals when items are not being printed and to move the carriage endwise when a total is printed, whether items are being printed or not.
